ELECTRIC BROILER SPATTER SHIELD

Max Steinbook, New York, N. Y., assignor to The Peerless Corporation, New York, N. Y., a corporation of New York

Application August 7, 1953, Serial No. 26,353

Term of patent 14 years

(Cl. D81—10)

FIG. 1

FIG. 2

FIG. 3

FIG. 4

To all whom it may concern:

Be it known that I, Max Steinbook, a citizen of the United States and a resident of the city, county, and State of New York, have invented a new, original, and ornamental Design for an Electric Broiler Spatter Shield, of which the following is a specification, reference being had to the accompanying drawing, forming part thereof.

In the drawing:

Fig. 1 is a top plan view of an electric broiler spatter shield embodying my design;

Fig. 2 is a front elevation;

Fig. 3 is a rear elevation; and

Fig. 4 is a left end view thereof.

I claim:

The ornamental design for an electric broiler spatter shield, as shown.
